DESIGN FOR A RECORD PLAYER

Lloyd J. Andres, Chicago, Ill.

Application August 28, 1944, Serial No. 115,068

Term of patent 7 years

(CL. D56—4)

To all whom it may concern:

Be it known that I, Lloyd J. Andres, a citizen of the United States and resident of Chicago, in the county of Cook and State of Illinois, have invented a new, original, and ornamental Design for Record Player, of which the following is the specification, reference being had to the accompanying drawing, forming a part thereof.

Fig. 1 is a front perspective view of a record player showing my new design, the records being indicated by means of dotted lines for illustrative purposes only; and

Fig. 2 is a rear perspective view thereof with the records omitted.

I claim:

The ornamental design for a record player, as shown and described.

LLOYD J. ANDRES.
